United States Patent

Des. 240,278
Patented June 8, 1976

240,278

VITREOUS CUTTER

David E. Staub, Clearwater, Carl L. Foltz, Holiday, and
Raymond W. Simmons, Pinellas Park, Fla., assignees to
Concept, Inc.

Filed Dec. 12, 1974, Ser. No. 531,967

Term of patent 14 years

Int. Cl. D8—01; D24—02
U.S. Cl. D63—12 R

Fig. 1.

Fig. 2.

Fig. 3.

Fig. 4.

FIG. 1 is a side elevational view of a vitreous cutter showing the new design with the opposite side being substantially a mirror image thereof;

FIG. 2 is a front elevational view of the vitreous cutter illustrated in FIG. 1;

FIG. 3 is a front end elevational view of FIG. 1; and

FIG. 4 is a rear end elevational view of FIG. 1.

What is claimed is:

The ornamental design for a vitreous cutter, substantially as shown.
